UNITED STATES PATENT OFFICE.

CHARLES S. PEDERSON, OF GRANTSBURG, WISCONSIN.

PORABLE FIREPROOF SAFE.

1,038,428.

Specification of Letters Patent. Patented Sept. 10, 1912.

Application filed February 29, 1912. Serial No. 680,570.

To all whom it may concern:

Be it known that I, CHARLES S. PEDERSON, a citizen of the United States, residing at Grantsburg, in the county of Burnett, 5 State of Wisconsin, have invented certain new and useful Improvements in Portable Fireproof Safes; and I do hereby declare the following to be a full, clear, and exact description of the invention, such as will 10 enable others skilled in the art to which it appertains to make and use the same.

This invention relates to improvements in fireproof receptacles, and has particular reference to a small receptacle for use in protecting jewelry or for packages of papers.

The principal object of my invention is to provide a device of this character which may be conveniently carried around in a hand grip or suit case, and be ample protection 20 against loss of valuables by fire.

Other objects and advantages will be apparent from the following description and with particular reference to the accompanying drawings.

25 In the drawings: Figure 1 is a side elevation of a device made in accordance with my invention. Fig. 2 is a horizontal section on the line 2--2 of Fig. 1. Fig. 3 is a vertical longitudinal section of the device.

30 Referring particularly to the drawings, my safe comprises a receptacle 10, and a lid 11, which may be secured thereto in any suitable manner, the means shown being the pins 12 in the upper end of the receptacle, for engagement in the bayonet slots 13 in the lower portion of the lid or cover. 35 The receptacle 10 and the lid 11 are of prac-

tically the same construction and it is thought that the description of the receptacle will be sufficient for both. The receptacle comprises an outer metallic shell 14, within which is arranged a lining of asbestos 15, and an inner metal wall 16, on the outer face of which is arranged a cork sheeting 17. Between the asbestos and the cork sheeting is arranged a metallic corrugated sleeve 18 which suitably spaces the asbestos and cork, and provides a dead air space therebetween. Within the inner metallic shell are adapted to be placed valuables which it 50 is desired to protect against the fire.

The end wall of the lid, and the bottom of the receptacle are made up of similar layers, to those just described. A suitable lock 19 may be provided to hold the lid 55 against unauthorized removal.

The device is simple and may be conveniently carried around in a suitcase or hand grip, and will insure against loss of valuable papers or jewelry by fire.

What is claimed is:

A fireproof case comprising a receptacle and cover therefor, each consisting of an outer metallic shell, a layer of asbestos next to the shell, a corrugated metallic layer next to the asbestos, a layer of cork next to the last mentioned metal layer, and an inner lining of metal.

In testimony whereof, I affix my signature, in presence of two witnesses.

CHAS. S. PEDERSON.
